(57) **CLAIM**

We claim the ornamental design for the boring machine, as shown and described.

DESCRIPTION

FIG. 1 is a front perspective view of the boring machine embodying our design;

FIG. 2 is a rear perspective view of FIG. 1;

FIG. 3 is a front elevational view of FIG. 1;

FIG. 4 is a rear elevational view of FIG. 1;

FIG. 5 is a left side elevational view of FIG. 1;

FIG. 6 is a right side elevational view of FIG. 1; and,

FIG. 7 is a top plan view of FIG. 1.

The broken lines in the drawing illustrate portions of the boring machine that form no part of the claimed design.
